UNITED STATES PATENT OFFICE.

CLAYTON O. DEWEY, OF BROOKLINE, MASSACHUSETTS.

RECEIVED-SUPPORTING ATTACHMENT FOR DESK-TELEPHONE TRANSMITTERS.

1,247,234.

Specification of Letters Patent. Patented Nov. 20, 1917.

Application filed April 2, 1917. Serial No. 159,075.

To all whom it may concern:

Be it known that I, CLAYTON O. DEWEY, a citizen of the United States, residing at Brookline, in the county of Norfolk, and State of Massachusetts, have invented new and useful Improvements in Receiver-Supporting Attachments for Desk-Telephone Transmitters, of which the following is a specification.

10 This invention relates to an attachment adapted to be engaged with the post of the transmitter forming a part of an ordinary desk telephone set, and to support the telephone receiver in operative relation to the transmitter mouth-piece, so that the user of the set may have the free use of both hands, when necessary, while carrying on a telephone conversation.

15 The invention has for its object to provide an attachment of this character having provisions for adjustably supporting the receiver when it is in use, in such manner as to meet the individual requirements of all users, the attachment being capable of such 20 adjustments as to mechanically compel the user to assume, with relation to the transmitter mouthpiece, a correct speaking position when the receiver is supported in correct hearing position.

25 The invention also has for its object to provide an attachment which, while presenting the possibilities above mentioned, does not interfere with the accustomed and ordinary use, mechanically, electrically, or otherwise, of the operation of a desk telephone set 30 as installed by a telephone company.

The invention is embodied in the improvements which I will now proceed to describe and claim.

40 Of the accompanying drawings forming a part of this specification,—

Figure 1 is a top plan view of a telephone set and an attachment embodying my invention applied thereto.

45 Fig. 2 is a front view of the same.

Fig. 3 is a section on line 3—3 of Fig. 2.

Fig. 4 is a section on line 4—4 of Fig. 2.

Fig. 5 is a section on line 5—5 of Fig. 2.

50 Fig. 6 is a section on line 6—6 of Fig. 2.

Figs. 7 and 8 are side elevations of a telephone set and an attachment constituting another embodiment of my invention applied thereto.

55 Fig. 9 is a top plan view of the same.

Fig. 10 is a section on line 10—10 of Fig. 8.

Fig. 11 is a section on line 11—11 of Fig. 8.

Fig. 12 is a section on line 12—12 of Fig. 8.

Fig. 13 is a section on line 13—13 of Fig. 8.

Fig. 14 is a section on line 14—14 of Fig. 8.

My invention is embodied in a receiver holder comprising a body portion provided with clamping means whereby it may be detachably engaged with the post 12 of a telephone transmitter, and held in a fixed position relatively to said post, an end portion standing at an angle to the body portion, and a transmitter rest connected with the said end portion, said holder being adapted to support a telephone receiver 13 in operative relation to the transmitter mouth-piece 14, when the said body portion is secured to the post.

I will first describe the preferred embodiment of the invention shown by Figs. 1 to 6, inclusive.

In said figures, 15 designates the body portion of the holder, which is an elongated rod provided between its ends with clamping means adapted to be secured to the reduced upper portion of the post 12 in a substantially horizontal position with its opposite ends located at opposite sides of the post. In this case, I have embodied the clamping means in a jaw 16 (Fig. 3) forming a part of the body portion 15 and a complementary jaw 17, adjustably secured by clamping screws 18, said jaws being formed to embrace the reduced upper portion of the post. When the screws are tightened, the body portion 15 is firmly secured to the post 12 and extends crosswise thereof, as shown by Figs. 1 and 2. The body portion 15 is subdivided by the clamping means into two arms projecting in opposite directions from the post 12, one of said arms carrying the receiver rest hereinafter described, while the other arm is weighted to counterbalance the rest and its load.

The end portion 19 of the holder is of angular form and includes an inner member which is slidable in a longitudinal socket in one of the arms of the body portion 15, and an outer member which is inclined relatively to the inner member and body portion. A set screw 20 engaged with one end of the body portion 15 secures the end portion 19 at various adjustments, the holder

being of telescopic construction. Said end portion 19 constitutes an extension of one of the arms of the body portion 15.

21 represents a receiver rest, which may 5 be made of sheet aluminum, or other suitable metal, and is formed to engage the under side of the receiver 13 between the ends thereof, as indicated by Figs. 1 and 2, said rest being connected with the end portion 10 19.

The angular form of the end portion 19 locates the rest 21 in an operative relation to the transmitter mouth-piece 14, as indicated by Figs. 1 and 2.

15 The inclined member of the end portion 19 is preferably of telescopic construction, and therefore variable in length to vary the height of the rest 21, the inclined member of said end portion being tubular, and receiving a stem or rod 23 which is movable 20 endwise to vary the height of the rest, and is secured at different heights by a set screw 24.

The rest 21 is preferably connected with 25 the end portion 19 of the holder by means permitting swinging adjustments of the rest in a vertical plane and in a horizontal plane, said connections as here shown, being embodied in the rod or stem 23, ears 25 formed 30 on the upper end of said stem, an ear 26 attached to the rest 21 and projecting between the ears 25, and a clamping screw 27 passing through said ears and constituting a pivot on which the rest may be swung in 35 a vertical plane, the stem 23 being adapted to turn in the end member 19 to permit a swinging adjustment of the rest in a horizontal plane. When the screws 24 and 27 are tightened, the rest is confined at the 40 desired adjustment.

It will be seen that the adjustments permitted by the described means and by the sliding connection between the body portion 15 and end portion 19, permit all adjustments of the rest which may be required to suit the requirements of all telephone users. The body portion arm at the left of the clamping means, as viewed in Figs. 1 and 2, and the end portion or arm extension 50 19 project from one side of the axial plane of the mouth piece 14. The other body portion arm projects from the opposite side of said plane, and may be called the inner arm.

To counterbalance the weight of the rest 55 and load (the receiver) and thus prevent liability of a tipping displacement of the transmitter when the receiver is on the rest, I provide the inner arm of the holder with counterbalancing means, which may be embodied in a weight 28 attached to the end of the said inner arm, opposite the end thereof which is engaged with the end portion 19, so that the weight is located at one 60 side of a line intersecting the center of gravity of the post, while the rest 21 and

its load are located at the opposite side of the said line.

The described holder may be used to support a timing device, in position to be viewed by the user while speaking into the 70 mouth-piece 14, said device being preferably embodied in a so-called hour-glass 29, which may be adapted to run for a relatively short period, say, three minutes. The frame of the hour-glass is adapted to rotate on one 75 end of the holder, said frame as here shown being provided with a socket 30, journaled on one end of the body portion 15 of the holder. The hour-glass, therefore, may be inverted whenever its use is required. The 80 socket 30 may be confined by any suitable frictional means, permitting it to be turned by the application of suitable force. The hour-glass may be of sufficient weight to constitute the counterbalancing means, the 85 weight 28 being omitted.

In the embodiment of the invention shown by Figs. 7 to 14, inclusive, the body portion 15^a of the holder is vertically arranged and constitutes a standard, adapted to bear at 90 its lower end on a desk top 32 or other horizontal base, beside the foot of the transmitter post 12, the weight of the holder and of the receiver rest being sustained entirely by said base.

The end portion 19^a includes an inner member adapted to slide in the tubular member 15^a, and is secured by a set screw 20^a, so that the height of the rest may be varied.

The body portion 15^a, may have a foot 33 of rubber bearing on the base 32.

The body portion is detachably engaged with the post 12 and confined in a vertical position suitably spaced from the post foot 100 105 to bear on the base 32, as indicated by Fig. 8, by clamping means embodied in upper and lower folded metal strips 34, Figs. 13 and 14, each having a looped neck portion 35 embracing the body portion 15^a, and segmental end portions or jaws 36 forming compressible sockets adapted to embrace different portions of the post 12.

As shown by Figs. 8, 13 and 14, the jaws of the upper strip 34 are formed to embrace 115 the reduced upper portion of the post, while the jaws of the lower strip are formed to embrace the larger portion of the post near the foot thereof.

Clasps 37, embracing and movable on the 120 strips 34, are adapted, when moved toward the jaws 36, to press said jaws into firm, frictional engagement with the post.

The rest 21 is mounted on the inclined outer member of the end portion 19^a, said 125 member and rest being provided with complementary connecting parts permitting the rest to swing in vertical and horizontal planes relatively to said arm, and thus vary the angularity of the rest.

Said complementary connecting parts, as here shown, comprise a stud 39, Fig. 10, adapted to turn in the (tubular) end portion 19^a, and provided with an eye 40 at its outer end, a pivot-pin 41 attached to, and projecting downwardly from the rest 21 and adapted to turn in the eye 40, and a clamping-nut 42 engaged with a screw-threaded portion of the pin 41 and adapted, when set up, to firmly clamp the eye 40 against a seat 43 above said eye.

The stud 39 is adapted to slide endwise in the end portion 19^a, a set-screw 44 being provided to confine the stud at different adjustments, and to prevent said stud from turning.

It will now be seen that each embodiment of the invention constitutes an attachment which does not interfere in any way with either the mechanical or the electrical use of the telephone set, and that the association of the attachment with the telephone set is not objectionable. It will also be seen that provision is made for supporting the receiver in any position required by the user.

Incidentally, the use of the attachment compels the user to assume with relation to the mouth-piece of the transmitter, a correct speaking position, the lips being not too far removed from the mouth-piece. This is because the receiver, when deposited on the rest, is so near the mouth-piece that when the user's ear is against the receiver, his lips cannot be too far removed from the transmitter mouth-piece.

In each of the described embodiments of the invention, the receiver holder comprises a receiver rest such as 21, and an elongated angular telescopic frame composed in one embodiment of the invention of the base member 15, the outer member 23, and the intermediate angular member 19, and in the other embodiment of the invention of the base member 15^a, the outer member 39, and the intermediate angular member 19^a, said members being slidably connected, the base member being provided with clamping means adapted to engage a transmitter post, while the outer member is directly connected with the rest. Said members are provided with means such as the set screws 20 and 24 whereby they may be confined in different positions relatively to each other, to maintain various adjustments of the frame as to length. It will also be seen that in each case, the angular form of the intermediate member, said member being composed of an outer arm and an inner arm arranged at an angle with the outer arm, permits adjustment of the receiver rest in two directions relatively to the mouth-piece of a transmitter with which the frame is engaged.

I claim—

1. A receiver holder comprising a re-

ceiver rest, an elongated telescopic frame composed of an outer member directly connected with the rest, a base member provided with clamping means adapted to engage a transmitter post, and an intermediate angular member composed of an outer arm slidably connected with the outer member, and an inner arm slidably connected with the base member and arranged at an angle with the outer arm, the angular form of said intermediate member permitting adjustment of the rest in two directions relatively to the mouth-piece of a transmitter with which the frame is engaged, means being provided for confining the said members in different positions relatively to each other to maintain various adjustments of the frame as to length.

2. A receiver holder comprising a receiver rest, an elongated telescopic frame composed of an outer member, a base member provided with clamping means adapted to engage a transmitter post, an intermediate angular member composed of an outer arm slidably connected with the outer member, and an inner arm slidably connected with the base member, and means connecting the outer member with the receiver rest and having provisions for a swinging adjustment of the rest relatively to the frame, and for securing the rest to the frame in various adjustments, the angular form of said intermediate member permitting adjustment of the rest in two directions, relatively to the mouth-piece, of a transmitter with which the frame is engaged, means being provided for confining said members in different positions relatively to each other to maintain various adjustments of the frame as to length.

3. In combination with a portable telephone transmitter including a base and a post perpendicular thereto, a receiver holder comprising a receiver rest and an elongated angular telescopic frame composed of a plurality of slidably connected members, one member being provided with clamping means adapted to embrace the post without obstructing the base, while another member is connected with the rest, and a counterbalancing weight attached to one of the members of said frame, the relative arrangement of said rest, clamping means, and weight being such that, when the frame is engaged with the post, the rest and weight are at opposite sides of the center of gravity of the post.

4. A receiver holder comprising a receiver rest and an elongated angular telescopic frame composed of a plurality of slidably connected members, one of which is provided with clamping means adapted to engage a transmitter post, while another is connected with the rest, and a timing device secured to one of the members of said frame and constituting also a counterbalancing weight, the

- relative arrangement of said rest, clamping means, and timing device being such that, when the frame is engaged with a transmitter post, the rest and timing device are at opposite sides of the center of gravity of the post, and the timing device is located in sight of the user.
5. A receiver-holder comprising an elongated body portion, provided with clamping means adapted to detachably engage a transmitter post, and secure the body portion in a fixed position relatively to the post, an adjustable end portion adjustably engaged with said body portion and standing at an angle therewith, and a receiver rest connected with the outer end of the outer portion, said portions forming a telescopic holder adapted to support the rest in different relations to the transmitter mouth-piece when the body portion is engaged with a receiver post, means being provided for confining the outer portion in its adjusted positions.
- 10 6. A holder as specified in claim 7, in which the said outer portion and rest are provided with complementary connecting parts permitting swinging adjustments of the rest relatively to the outer portion, means being provided for confining the rest in its adjusted positions.
- 15 7. A holder as specified in claim 8, in which said connecting parts are organized to permit swinging adjustments of the rest

in a substantially horizontal plane, and in a substantially vertical plane.

8. A receiver holder comprising an elongated body provided with clamping means adapted to engage a transmitter post and hold said body crosswise of the post, said body forming two arms projecting in opposite directions from the clamping means and from a post engaged thereby, a receiver rest, connections between said rest and one of said arms whereby the rest may be operatively located relatively to the transmitter mouth-piece, at one side of the axial plane of the mouth-piece and of the center of gravity of the post, the other arm of said body projecting from the opposite side of said plane and being weighted to counterbalance the rest and its load.

9. A receiver-holder comprising an elongated body portion having clamping means adapted to detachably confine said portion in a substantially horizontal position on a transmitter post, an angular end portion including an inner member movable relatively to said body portion to vary the length of the holder, and an inclined outer member standing at an angle with the inner member, and a receiver rest connected with the said inclined member.

In testimony whereof I have affixed my signature.

CLAYTON O. DEWEY.
